UNITED STATES PATENT OFFICE.

ROBERT DIAL, OF RAMSEY, ILLINOIS, ASSIGNOR OF ONE-HALF TO NOAH D. JENNINGS, OF SAME PLACE.

CAR-COUPING.

SPECIFICATION forming part of Letters Patent No. 434,385, dated August 12, 1890.

Application filed May 21, 1890. Serial No. 352,637. (No model.)

To all whom it may concern:

Be it known that I, ROBERT DIAL, a citizen of the United States, residing at Ramsey, in the county of Fayette and State of Illinois, 5 have invented certain new and useful Improvements in Car-Couplers; and I do declare the following to be a full, clear, and exact description of the invention, such as will enable others skilled in the art to which it appertains to make and use the same.

My invention relates to improvements in car-couplers; and it has for its object to provide a device which when a link-pin has been raised to allow the entrance of a link into the draw-head will automatically assume a position beneath said pin and support the same in the raised position until said supporting device is pressed backward by the impingement of the coupling-link against the lower 20 portion thereof, when the pin is allowed to fall and the coupling is effected without the necessity of the attendant remaining between the cars during the operation.

The novelty will be fully understood from 25 the following description and claims, when taken in connection with the accompanying drawings, in which—

Figure 1 is a side elevation of a railway-car body carrying my improvements, the draw-head being shown in vertical section to illustrate the latter. Fig. 2 is a detail front elevation of the spring-arm and the bracket attached thereto for the support of the link-pin.

In carrying out my invention I may employ 35 the ordinary draw-head now in use, but slight modifications thereof being necessary to adapt it for the operation of my improvements.

The lip *a* of the draw-head *A*, as better illustrated in Fig. 1, is of a construction to 40 readily receive and guide the coupling-link into the draw-head without the assistance of an attendant. The top wall of the draw-head is slotted longitudinally, as illustrated, to afford space for the forward play of the arm, 45 and in the said draw-head I form an interior recess *b*, which extends forwardly to the ordinary vertical pin-aperture *c*, and is designed for the reception and play of the forwardly-extending bracket-pin support of the 50 spring-arm.

The spring-arm *B*, which is preferably of the proportional width, as illustrated in Fig. 2, is secured to the front of a car at a correct distance above and in line with the draw-head, an angular block *C* being attached to 55 the car-wall directly below the attaching-point of the spring-arm and in line therewith, whereby the said arm is pitched forwardly and normally assumes the position shown in full lines in Fig. 1. The angular bracket *D* 60 is secured to the spring-arm *B*, by bolts passing through the vertical branch thereof, at an elevation suitable to allow the horizontal pin-supporting branch of said bracket to move within the recess *b* of the draw-head. 65

Although the construction of spring-arm and bracket illustrated is preferable, yet it is obvious that the horizontal forwardly-extending branch might be formed integral with the spring-arm and perform its functions in an equally satisfactory manner. 70

E indicates the link-pin, and *F* the link of the coupler, which may be of any ordinary or approved construction.

In Fig. 1 I have illustrated mechanism 75 whereby the pin may be raised by an attendant upon the top of the car, when it will be seen that the horizontal branch of the bracket *D* will assume a position beneath the pin and support it in the raised position until the 80 coupling-link presses the spring-arm back and allows the pin to fall.

G indicates a vertical rod, which connects the link-pin with the end of a lever *H*, which is fulcrumed in upright standards *I* at the top 85 of the car.

In operation the link-pin of the car having been raised, is supported by the horizontal branch of the spring-arm, which normally assumes the position shown in full 90 lines, and holds the pin up until the link in the draw-head of the car to be coupled enters the draw-head and presses back the lower end of the spring-arm, and consequently the bracket-support allows the pin 95 to fall and the coupling is effected.

It is obvious that the construction of my improvements may be materially altered to perform the functions set forth without departing from the spirit of my invention. 100

Having described my invention, what I claim is—

1. The combination, with a draw-head having its top wall slotted longitudinally and provided with an interior recess, of the spring-arm having its upper end secured to the car-front above and in line with the draw-head, and the forwardly-extending horizontal bracket moving in the interior recess of the draw-head and adapted to support the pin in a raised position, substantially as described.
2. The combination, with the draw-head having its top wall slotted and its interior recessed, as described, and the spring-arm having its upper end secured to the car-front above and in line with the draw-head and carrying the forwardly-extending bracket-arm, of the link-pin, the operating-lever journaled in standards at the top of the car, and the bar connecting the link-pin with the op-

erating-lever, substantially as and for the purpose specified.

3. In a car-coupler, the combination, with the draw-head having its top wall recessed longitudinally and provided with the interior recess and vertical pin-receiving aperture, of the spring-arm secured to the car-wall in line with the longitudinal slot in the draw-head, and provided with the bracket-pin support at a point above its lower end, which extends down to receive the impingement of the coupling-link, substantially as and for the purpose specified.

In testimony whereof I affix my signature in presence of two witnesses.

ROBERT DIAL.
